DESIGN FOR A HANDBAG

Martin Ginsburg, Brooklyn, N. Y.

Application April 26, 1943, Serial No. 110,046

Term of patent 3½ years

(Cl. D87—3)

To all whom it may concern:

Be it known that I, Martin Ginsburg, a citizen of the United States, residing in the Borough of Brooklyn, county of Kings, city and State of New York, have invented a new, original, and ornamental Design for a Handbag, of which the following is a specification, reference being had to the accompanying drawing, forming part thereof.

On the drawing,

Fig. 1 is front elevational view of a handbag

embodying my new design, and shown in closed position;

Fig. 2 is an end elevational view of the handbag; and

Fig. 3 is a view similar to Fig. 1, the handbag being shown opened.

I claim:

The ornamental design for a handbag, as shown.

MARTIN GINSBURG.
